UNITED STATES PATENT OFFICE.

PETER CARETTI, OF CONNELLSVILLE, PENNSYLVANIA.

SHOEMAKER'S TOOL.

1,016,608.

Specification of Letters Patent.

Patented Feb. 6, 1912.

Application filed November 24, 1911. Serial No. 662,233.

To all whom it may concern:

Be it known that I, PETER CARETTI, a citizen of the United States, residing at Connellsville, in the county of Fayette and State of Pennsylvania, have invented a new and useful Shoemaker's Tool, of which the following is a specification.

This invention relates to shoemaker's tools and particularly to heel shaves.

10 One object of the present invention is to provide a simple and inexpensive device of this character, which shall be convenient and efficient in use.

15 Another object of the invention is to provide a novel means for adjusting the guard for the blade.

20 A further object of the invention is to provide a heel shave of this character which may be employed to trim various styles of heels, such as Cuban, military or French heels, and which may be used for either straight or concaved heel edges.

25 To the above ends this invention resides in the novel construction and combination 25 of parts as hereinafter described and claimed, reference being had to the accompanying drawings, wherein—

30 Figure 1 is a side elevation of the heel shave. Fig. 2 is a bottom view thereof. Fig. 3 is a section on the line 3—3 of Fig. 2. Fig. 4 is a section on the line 4—4 of Fig. 2. Fig. 5 is a section on the line 5—5 of Fig. 1. Fig. 6 is a perspective view of the guard.

35 Referring in detail to the drawings, wherein similar reference characters indicate similar parts, there is designated by the numerals 11 and 11' a pair of handles which are curved or bowed upwardly and which are connected by a forward vertical bridge 19 and by a rear supplemental bridge 12 which is spaced from the former bridge. A curved guard 17 is arranged below the bridge 19 and has an upstanding lug 23 fitting into a corresponding recess 24 in the 40 bottom of the bridge 19, and the said lug 23 has an upstanding bolt 25 passing through the bridge 19 through an opening 20 therein. A nut 18 is arranged on the said bolt 25 and fits within the opening 20 to be constrained 45 against longitudinal movement in the bridge 19. The guard 17 is also provided with a pair of fingers or guides 26 at the sides of the lug 23 which project into the bridge 19 to constrain the guard against swinging. A 50 curved blade 13 is arranged between the guard 17 and the supplemental bridge 12

and has the extremities thereof secured to the respective handles 11 and 11'. One extremity of the blade 13 is secured to the handle 11' by a suitable screw 14, and the 50 other extremity thereof is bent angularly in an upstanding position as designated by the numeral 22 to fit on the inner face of a plate 16 secured to the inner end and outer side of the handle 11 and the angular extremity 22 55 is secured to the said plate 16 by means of a bolt 15. The guard 17, blade 13 and the supplemental bridge 12 are dropped below the handles and have a common gentle convex curve 28 at the bottom extending from 70 the handle 11 and forming a corner 27 therewith, then into an abrupt convex curve 29 toward the handle 11', and terminating in a gentle concave curve 30 merging into the 75 handle 11'.

In use, the guard 17 may be readily adjusted by rotating the nut 18, which in fitting in the opening 20 in the bridge 19 projects beyond the sides of the bridge 19 to permit the nut to be readily rotated, and by the rotation of the nut 18 on the bolt 25 it will be seen that the bolt is moved longitudinally to thereby move the guard 17 accordingly. By adjusting the guard 17 the 80 depth of the cut made by the blade 13 may 85 be regulated, and by reason of the shape of the guard, blade and the supplemental bridge this device may be used for trimming various styles of heels, such as Cuban, military or French heels, and may also be used 90 for either straight or concaved heels of various degrees in an efficient manner. The shavings pass into the space 21 between the bridges 19 and 12 and may be readily removed. The blade 13 abuts against the supplemental bridge 12 and is thereby braced 95 against being sprung rearwardly when in use, and this blade may be readily detached for sharpening or replacement.

This tool is convenient in use and will not 100 cut the uppers of the shoe in trimming the heels thereof. This tool is also simple in construction thereby rendering it inexpensive to manufacture and as a whole presents 105 a desirable tool of this character.

What is claimed is:

1. In a heel shave, a pair of handles connected by a bridge, a curved guard arranged below the bridge having a bolt upstanding therefrom and passing through the bridge, 110 a nut on the said bolt and constrained against longitudinal movement in the said

bridge, and a curved blade connected at its extremities to the handles in rear of the guard.

2. In a heel shave, a pair of handles connected by a front bridge and a curved rear supplemental bridge spaced from the former bridge, a curved guard arranged below the former bridge and having a bolt upstanding therefrom and passing through the former bridge, a nut on the said bolt and constrained against longitudinal movement in the former bridge, and a curved blade connected at its extremities to the handles between the guard and the supplemental bridge, the said guard, blade and supplemental bridge being dropped below the handles and having a common gentle convex curve at the bottom extending from one of the handles and forming a corner therewith, then into an abrupt convex curve toward the other handle, and terminating in a gentle concave curve merging into the last mentioned handle.

3. In a heel shave, a pair of handles connected by a front bridge and a curved rear supplemental bridge spaced from the former bridge, a curved guard arranged below the former bridge and having a bolt upstanding therefrom and passing through the former

bridge, a nut on the said bolt and constrained against longitudinal movement in the former bridge, a curved blade connected at its extremities to the handles between the guard and the supplemental bridge, the said guard, blade and supplemental bridge being dropped below the handles and having a common gentle convex curve at the bottom extending from one of the handles and forming a corner therewith, then into an abrupt convex curve toward the other handle, and terminating in a gentle concave curve merging into the last mentioned handle.

In testimony that I claim the foregoing as my own, I have hereto affixed my signature in the presence of two witnesses.

PETER CARETTI.
